UNITED STATES PATENT OFFICE.

JOHN A. THOMPSON, OF AVERY, IOWA.

TRACTION-ENGINE.

1,176,182.

Specification of Letters Patent. Patented Mar. 21, 1916.

Application filed June 15, 1915. Serial No. 34,317.

To all whom it may concern:

Be it known that I, JOHN A. THOMPSON, a citizen of the United States, and resident of Avery, in the county of Monroe and State of Iowa, have invented a certain new and useful Traction-Engine, of which the following is a specification.

5 The object of my invention is to provide a traction engine of simple, durable and inexpensive construction.

10 A further object is to provide a traction engine particularly adapted for hauling cars in mines and the like, so constructed and arranged for hauling maximum grades with a minimum of engine weight.

15 A further object is to provide such an engine adapted to wind a cable from a drum or drums to propel the engine along a track.

20 A further object is to provide in an engine of the type mentioned, guide devices for guiding the taking up of the cable and the replacement of the cable in the proper place along the track.

25 Still a further object is to provide an engine of this type having means for properly guiding and laying a cable in connection with guide devices on the right away, whereby the cable may be properly placed 30 in position after it has traveled over the drums on the engine.

In view of these and other objects, my invention consists in the construction, arrangement and combination of the various 35 parts of the device whereby the objects contemplated are attained, as hereinafter more fully set forth pointed out in my claims and illustrated in the accompanying drawings, in which:

40 Figure 1 shows a side elevation of a traction engine embodying my invention. Fig. 2 shows a top or plan view of the same. Fig. 3 shows a detail plan view of a portion of the gearing device of the engine. Fig. 4 shows a detail end view of one of the 45 pairs of guide pulleys. Fig. 5 shows a detail view partly in section of the means for securing one end of the cable. Fig. 6 shows a plan view of a portion of the track illustrating the manner in which the cable is 50 laid at a junction point. Fig. 7 shows a detail sectional view of the track and guide rail taken on the line 7—7 of Fig. 6, portions of one pair of pulleys being shown 55 in end elevation, illustrating the relation of the pulleys to the rails of the track and

the guide rail, and Fig. 8 shows a side elevation of a portion of one of the rails illustrating the notch cut therein to admit the cable.

60 In the accompanying drawings, I have illustrated one form of my invention, and have employed the reference numeral 10 to indicate generally the ties of a track on which are placed the rails 11.

65 In Fig. 6 I have shown a junction point between two tracks. It is my purpose to operate my engine in connection with and partially by means of a cable 12 laid along the center of the track over which the engine is to travel. The cable 12 at one, or if desired, at both ends may be connected with a powerful coil spring 13, which in turn is connected with a flexible device or cable 14 wound on a drum 15, rotatable on 70 an anchored support 16. On the drum 15 is a ratchet 17, adjacent to which on the support 16, is a pawl 18. Pivotedly mounted on the drum shaft 19 is a lever 20, on which is a pawl 21. The pawls 18 and 21 are adapted to coact with the ratchet 17. By means of the mechanism just described, the tension on the cable 12 may be varied as may be desired, and it is also possible to allow some give to the cable, 85 which is desirable in making curves.

80 At the junction points, the cable 12 is held in the middle of the track between the rails by means of a guide rail 22, which is preferably somewhat higher than the 90 rails 11 for a purpose which will be hereafter described. The rail 11, which is crossed by the cable 12, is provided with a notch 23 to admit the cable 12.

95 My improved engine comprises a truck which may be built with the elliptical frame 24 having the parallel longitudinal frame members 25, as clearly illustrated in Fig. 2.

100 Mounted on the frame 24 in suitable bearings 26 are spaced axles 27, on which are fixed supporting wheels 28. Suitably mounted on the truck is an engine 29 having the shaft 30, as shown in Figs. 2 and 3. Below the engine shaft 30 is a transverse shaft 31 extending across the machine and mounted in suitable bearings.

105 On the engine shaft 30 is loosely mounted a sleeve 32, formed on which is a pinion 33 and a cone clutch member 34. The pinion 33 is in mesh with a pinion 35 on the shaft 31.

110 Spaced from the sleeve 32 on the shaft 30

is loosely mounted a sleeve 36, formed on which is a sprocket gear 37 and a cone clutch member 38 opposite the clutch member 34. On the shaft 31 is a sprocket gear 38^a in line with the sprocket gear 37. A chain 39 travels on the sprockets 37 and 38^a. Slidably but non-rotatably mounted on the shaft 30 between the clutch members 34 and 38 is a sleeve 40, formed on which are cone clutch members 41 and 42 adapted to engage and coact respectively with the clutch members 34 and 38 in different positions of the sliding movement of the sleeve 40. The sleeve 40 is designed to be controlled in any suitable way.

15 Mounted in suitable bearings 43 on the frame members 25, on opposite sides of the engine, are transverse shafts 44 on which are mounted sheave drums 45 and 46. The cable 12 is wound over the drums 45 and 46.

20 On the shaft 31 are sprocket gears 47 and 48 in line with sprocket gears 49 and 50 respectively on the shafts 44. A chain 51 travels on the sprockets 47 and 49 and a chain 52 travels on the sprockets 48 and 50.

25 Suitable brakes are provided for the drums 45 and 46, which brakes are constructed as follows; the brakes are similar for each drum, and I will, therefore, describe but one. A resilient member 53 is pivoted to a suitable support 54 and extends upwardly and over the drum. A plurality of segmental blocks 55 of suitable material are secured to the under surface of the resilient member 53. The blocks 55 are adapted to fit into the grooves of the sheave drums and to engage the wall thereof, and also to engage the cable 12. The upper ends of the resilient members 53 are pivoted at 30 points between the ends of the levers. The upper end of the lever 56 adjacent to the drum 45 is pivoted to a supporting frame member 57. Pivoted to the lower end of the lever 56 is a link 58. The link 58 is also 35 pivoted to a lever 59, suitably pivoted on a frame member 60. The link 58 is pivoted to the lever 59 below the pivotal point of said lever. A lever 61, adjacent to the drum 46 is pivoted at its upper end to a supporting frame member 62, and its lower end to a link 63. The link 63 is pivoted to the lever 59 above the pivotal point of said lever. It will readily be seen that the arrangement of the parts is such that by moving the lever 59 in one direction, both the 40 brake devices will be released, and by moving it in another position both the brake devices will be tightened.

45 At each end of the frame is a guide device arranged to hold the cable 12 below and considerably spaced from the nearest axle 27. The guide devices comprise brackets 64 having opposite portions 65 extending downwardly and toward each other 50 and connected at their lower ends by a por-

tion 66. Rotatably mounted on the portion 65 are wheels 67 having peripheral flanges 68 arranged at one side of the rim of each wheel, as illustrated in Fig. 4. It will be seen that the flanges are arranged at the 55 sides of the wheels farthest from the brackets on which the wheels are mounted, and that the wheels are inclined, as illustrated in Fig. 4, so that the lower edges of the wheels almost touch each other, and so 60 that the cable 12 may be placed in the space between the rims and flanges of the wheels at the lower edges thereon, as illustrated in said Fig. 4. The lower edges of the flanges of the wheels 67 are arranged on the frame 65 so that they are just above the upper level of the rails 11, and so that they will just clear the rails 11 in passing from one track to another at a junction point.

65 In the practical use of my improved traction engine the cable 12 is installed in position along the track on which it is desired to operate the engine, and is wound over the drums 45 and 46 and centered beneath the guide wheels 67, as illustrated in Figs. 1 and 90 2. The tension on the cable may be regulated as desired by means of the pawl and ratchet device at the end of the cable. The cable is threaded on the outside of the curve along the guide rails 22 at junction points 95 through the slots 23 at said junction points.

70 The engine is propelled forwardly by starting the engine 29 with the brakes released. By throwing the clutch member 41 into engagement with the clutch member 34, 100 rotation in one direction will be imparted to the shaft 31, and therethrough to the drums which will rotate and cause the engine to travel along the cable. For reversing the direction of travel of the engine, 105 the sleeve 40 is moved longitudinally on the shaft 30 to throw the clutch member 42 into engagement with the clutch member 38.

75 One of the important features of my device is the means for handling the cable. 110 It will be noted that the guide devices are spaced considerably away from the axles longitudinally of the machine, so that on turning curves the cable 12 will be taken up clear of the guide rail 22 and laid down 115 spaced from said guide rail on the outside of the curve, so that the cable will always be left in proper position after my engine has passed the guide rail. The bracket devices may be used for retarding the travel 120 of the engine on down grades.

80 I have built and used a full sized working engine, and have found that with a comparatively light weight engine of this type it is possible to pull a very heavy load. 125 With engines, ordinarily used in mines, on account of the steep grades found in the mine tunnels, it is necessary to have a very heavy engine in order to pull the coal cars. This entails a large expense in manufac- 130

turing, upkeep and fuel. With a device of this kind traveling with the cable, the engine may be comparatively light, and for that reason be made at a much less expense than the ordinary mine engine.

It will readily be seen that the cable may be readily taken up and placed, and changed from one track to another when it is desired.

It will be understood that many changes may be made in the arrangement and construction of the parts of my improved traction engine without departing from its essential features and purposes, and it is my intent to cover by this application any such changes which may be included within the scope of my claims.

I claim as my invention.

1. In a device of the class described, a frame, supporting wheels thereon, a pair of sheave drums mounted on said frame, a source of power mounted on the frame, means for operatively connecting the source of power with said drums, whereby rotary motion may be simultaneously imparted to the drums in the same direction, and means controlled from a single lever for frictionally retarding the motion of the drums, said means comprising a support adjacent to each drum, a flexible band brake member pivoted to the respective supports and adapted to extend circumferentially part way around a portion of the drum, a plurality of segmental blocks on the under surface of each flexible member, a lever pivotally supported between its ends, links extending toward the respective drums and pivoted to said lever on opposite sides of the pivotal point thereof, a pivoted lever adjacent to one flexible device and to one of said links, and a pivot lever pivoted to the other of said flexible devices and to the other of said links.

2. In a device of the class described, a frame, axles on said frame, wheels on said axles, a source of power mounted on said frame, a sheave drum mounted on said frame, and means for imparting motion to said drum in either direction at the option of the operator, guide devices adapted to receive and feed the cable located at the front and rear of the machine below and considerably spaced from the axles, whereby the cable will be fed on the outside of the curve of the center of travel of the machine upon making turns, said guide devices comprising at each end of the machine a bracket having spaced members inclined downwardly and toward each other, sheaves pivoted to the said members having their lower portions adjacent to each other, said sheaves having their adjacent flanges removed so that a cable may travel between the peripheries and flanges of the sheaves at their lower adjacent portions.

3. In a device of the class described, a

frame, axles on said frame, wheels on said axles, a source of power mounted on said frame, a sheave drum mounted on said frame, and means for imparting motion to said drum in either direction at the option 70 of the operator, guide devices adapted to receive and feed the cable located at the front and rear of the machine below and considerably spaced from the axles, whereby the cable will be fed on the outside of 75 the curve of the center of travel of the machine upon making turns, said means comprising at each end of the machine a pair of sheaves rotatably mounted and inclined from their upper portions downwardly and toward each other and having on their peripheries on the sides thereof adjacent to the sheaves an annular outwardly projecting flange whereby a cable may be received and fed between the peripheries and flanges of the sheaves at their 80 lower portions.

4. In a device of the class described, the combination of a frame mounted on wheels, sheave drums mounted on said frame, means for imparting motion to said drums simultaneously in the same direction with a cable wound on said drum, a track on which said wheels are adapted to travel, a curved railroad track, and a guide rail located between the rails of the track at the curve therein, said guide rail being higher than the rails of the track, said guide devices being arranged forwardly and rearwardly of the machine respectively from the axles and adapted to feed or take up said cable from the side of said guide rail on the outside of the curve.

5. In a device of the class described, the combination of a frame mounted on wheels, 105 drums mounted on said frame for rotation, means for imparting motion to said drums, a track on which said wheels are adapted to travel, a curved switch track leading from the first track, a guide rail higher than the 110 switch track, rails arranged between the rails of the switch track at the curved portions thereof, one rail of the main track between the rails of the switch track having a slot to receive a cable, a cable extended along a portion of the first track and along the switch track adjacent to said guide rail on the outside of the curve and received in said slot, and guide devices on said frame spaced rearwardly and forwardly respectively from the wheels thereof and adapted to take up and feed said cable from the side of said guide rail.

6. In a device of the class described, the combination of a frame mounted on wheels, 125 drums mounted on said frame for rotation, means for imparting motion to said drums, a track on which said wheels are adapted to travel, a curved switch track leading from the first track, a guide rail higher 130

- than the switch track, rails arranged between the rails of the switch track at the curved portions thereof, one rail of the main track between the rails of the switch track having a slot to receive a cable, a cable extended along a portion of the first track and along the switch track adjacent to said guide rail on the outside of the curve and received in said slot, guide devices on said frame spaced rearwardly and forwardly respectively from the wheels thereof and adapted to take up and feed said cable from the side of said guide rail, and resilient adjustable means for securing one end of said cable.
7. In a device of the class described, the combination of a frame mounted on wheels, drums mounted on said frame, means for imparting motion to said drums in either direction at variable speeds, with a track on which said wheels are adapted to travel, a switch track leaving said first track, a cable adapted to lie along one of the tracks or along the switch track and part of the main track, said cable being wound on said drums, and guide, feed and take-up devices located on said frame rearwardly and forwardly respectively from the wheels there-

of, and adapted to pick up said cable from the bed of the track in front of the machine and to place the cable in the track in the rear of the machine.

8. In a device of the class described, the combination of a frame mounted on wheels, a source of power thereon, drums on said frame, a curved track on which said wheels travel, a cable laid along said track and wound on said drums, and coating guide, feed and take-up devices on said frame and track whereby said cable is taken up and laid down in a certain position with relation to the rails of the track.

9. In a device of the class described, the combination of a cable operated traction engine, with a track and a switch track leading therefrom, a cable, said engine, tracks and cable being so arranged that the engine may be operated on one track and the cable so fed and taken up as to permit loaded cars to travel across the cable on the other track.

Des Moines, Iowa, April 2, 1915.
